UNITED STATES PATENT OFFICE.

JOHN SCOTT BUBB, OF KITTANNING, PENNSYLVANIA.

AUTOMATICALLY-OPERATED BICYCLE-PUMP.

SPECIFICATION forming part of Letters Patent No. 631,773, dated August 29, 1899.

Application filed October 1, 1898. Serial No. 692,396. (No model.)

To all whom it may concern:

Be it known that I, JOHN SCOTT BUBB, residing at Kittanning, in the county of Armstrong and State of Pennsylvania, have invented a new and Improved Automatically-Operated Bicycle-Pump, of which the following is a specification.

This invention relates to improvements in bicycle-pumps connected to the bicycle-frame and adapted to be conveniently shifted into or out of an operative position by the rider while mounted on the machine; and in its general nature such invention comprehends a novel construction or pumping and distributing mechanism adapted to be disposed within the frame-tubing and so arranged as to be operated by an eccentric of crank mechanism connected with either the drive-wheel axle or the crank-axe. In its subordinate features this invention consists in certain details of construction and peculiar combination of parts, all of which will be first described in detail and then specifically pointed out in the appended claims, reference being had to the accompanying drawings, in which—

Figure 1 is a vertical section of the bicycle-frame, showing my improvements applied, the drive and sprockets being indicated in dotted lines. Fig. 2 is a transverse section of the crank-axe on the line 2 2 of Fig. 1. Fig. 3 is a transverse section of one of the wheel-axes. Fig. 3^a is a detail view of one of the axles and its attached parts. Fig. 3^b is a detail view illustrating a modified arrangement of the parts shown in Fig. 3. Fig. 4 is a detail view, on an enlarged scale, of the several parts constituting such axle detached. Fig. 5 is a detail view illustrating the funnel connections for joining the air or distributing pipes with the hollow axle. Fig. 6 is a side elevation, parts being in section, of a bicycle-frame having the pumping mechanism located in one of the horizontal frame-tubes and also illustrating a modified arrangement of distributing-pipes and rubber tubing in the manner of connecting them to the hollow axles. Fig. 7 illustrates a further modification of my invention which will hereinafter be particularly referred to. Fig. 8 is a detail view illustrating another way in which to connect the pipes with the hollow

axle. Fig. 9 is a detail of still another way of connecting the air-delivery pipe to the hollow axle. Fig. 10 is a detail view illustrating one way of connecting the crank-axe with the pump-rod. Fig. 11 illustrates another form of clutch-shifting devices for throwing the pump mechanism into and out of an operative condition.

Referring to the accompanying drawings, and more particularly to the construction shown in Figs. 1 to 5, inclusive, 1 indicates the crank-axe; 2, the rear-wheel axle; 3, the front-wheel axle, and 2^a the rear wheel and 3^a the front wheel, each of which has the usual pneumatic or inflatable tire.

In the construction shown the crank-axe has an eccentric 5 loosely mounted thereon, which is adapted to be clutched with the crank-axe at the will of the operator by suitable clutch mechanism—as, for example, such as illustrated in Fig. 2, by reference to which it will be seen that the sliding cuff member 7, which is normally held out of engagement with the eccentric 5 by a coil-spring 6, the said cuff member 7 being locked on the axle to turn therewith by a pin 8, it having a limited longitudinal movement on the axle by reason of its slot 7^a, in which the pin 8 plays. The face of the cuff 7 adjacent the eccentric 5 has one or more recesses 70, adapted to engage with pins projected laterally from the eccentric when the cuff is moved to the clutching position. 9 indicates a collar reciprocally slidable on the axle 1 by means of an operating-rod 10, movable within the seat-tube 11, slidably in suitable guides 11^a, held therein, and having at the outer end an angle or grip member 10^a, which projects through an elongated opening 11^b on the said tube and arranged within convenient reach of the rider, so that he can readily pull or push the rod 10 to adjust the clutch devices as desired. The lower end of the rod carries a pair of opposing beveled lugs 12 and 12^a, adapted to engage with cut-out portions of the collar 9, so that the movement of the rod 10 in one direction will slide the collar to force the cuff inward against the spring and in the other direction move the collar back to allow the spring to throw the clutch-cuff out of gear with the eccentric. By providing a clutch mechanism capable of operating and being

operated as described it is obvious the rider can set the eccentric in and out of gear at will without dismounting.

13 indicates the pump, which may be of any approved construction. This pump is located in the tube 11 and has its piston 13^a pivotally connected to the end 14^a of the eccentric band or strap 14, which may be engaged with the smooth or grooved periphery on the eccentric.

10 15 indicates the main distributing-pipe, which extends from the pump-discharge up to the joint of the seat-tube of the top horizontal tube 16 and the rear tube-section 17, which has at such point a T-coupling 18, with 15 which connect the rear distributing-pipe 19 and the front-wheel feed-pipe 20, having a rubber tube portion 20^a. The rear pipe 19 extends down into one of the back forks or tube-sections—in practice to a point near the axle—20 and connects with a flexible section 21, in turn joined with the upper end of the tube 22, the lower end of which carries a male funnel-section 23, having a closure-cap 24. The section 23 is adapted to engage a female funnel-section 25, which communicates with the hollow axle 2 of the rear wheel, the peculiar construction of such axle being best illustrated in Figs. 3, 3^a, and 3^b, as will be presently explained. The funnel-section 23 is normally 30 held down for an air-tight connection with the funnel-section 25 by the spring 26, disposed about the tube 22 and held to engage a fixed cross member 27 of the frame, and the collar 27^a, fixedly held on the tube 22.

35 To more clearly illustrate my invention, I have shown the members 22, 26, 27, and 24 disposed on the outside of the rear fork, as clearly shown in Fig. 1, yet I desire it understood that in practice such parts may be 40 inclosed entirely within the tubular member of the frame. The closure-cap 24 serves to keep the dust and dirt from entering the funnel-sections.

45 The pipe 20 extends forward into the hollow head-post and connects with a hollow flexible rubber tube portion 20^a, which passes down through the hollow frame to where the post goes through the crown-head of the fork, where it connects with the fork and from 50 whence it passes down on the inside of one of the forks 20^a and connects with the front axle through the male and female connections constructed and operated like the rear-axle connections before referred to.

55 As the funnel air connections are alike for both axles, a description of one will suffice for both.

60 Referring now more particularly to Figs. 3, 3^a, and 3^b, it will be observed that the axle 2 is made hollow at one end and formed with an air-receiving inlet x and an outlet y, which discharges centrally of the axle into what I term an "air-chamber" Z, which is formed by a division portion attached to and forming 65 a part of the hub-axle, as will be presently described.

In the practical adjustment of the axle and

the hub the hub is formed of a pair of integral or fixedly-held internally-threaded annular collars 32^a 32^a, which extend inward about 70 in a plane with the inner wall of the ball-bearing flanges 33^a, such collars 32^a 32^a being spaced on each side of the center of the hub, as shown. In joining the axle with the hub a disk 32^b is screwed into the collar 32^a, which 75 collar 32^a, together with the disk 32^b and the ring 40^a on the axle, forms one wall of the air-chamber Z when the parts are connected as shown in Fig. 3. Before the axle is fitted in its hub it is provided with a fixedly-held ring 80 40^a, against which, on the hollow-end side of the axle, is fitted a leather or rubber washer 34, a metal washer 35, an expansible spring 36, a second metal washer 35^a, a second leather or rubber washer 34^a, and a keyed air-tight-fitted ring 40, which is held against the washer 34^a by the flange 32^b of the disk 32^b, which disk is screwed into the collar 32^a, thereby 85 completing the other wall of the air-chamber Z, which has its outlet through the opening 31 90 and the pipe 42. The ball-bearing portions of the hub and axle may be of any approved construction. Instead of making the disks 32^b 32^b with stop-flanges to engage the axle-disk 40 40^a, as shown in Fig. 3, they may be 95 made without such stop-flanges, as shown in Fig. 3^b, as the washers 34 35 may be of sufficient diameter to be forced against the disks 32^a 32^a to make a proper air-tight connection. The air-chamber Z communicates, through 100 the tube 42, with the pneumatic tire 43, and such tube 42 screws up into the hub and down into the threaded orifice of the tire air-tube connections at the top and bottom, as shown. Instead of providing a separate air-tube for 105 connecting the tire and the hollow axle it is obvious that one of the wheel-spokes might be made hollow and used for such purpose. When using the funnel connections, the female funnel-section has an air-tight joint 110 with the axle.

115 43^a indicates a valve in pipe 19, and 45^a a similar valve in pipe 20.

So far as described the operation of my invention is best explained as follows: Assuming the valve 45^a to be closed and the valve 43^a in pipe 19 open and the operator desiring to inflate the rear-wheel tire, the rider by pushing the rod 10 down moves the clutch mechanism into a locked engagement with the eccentric, which causes the eccentric to operate and in consequence set the pump in motion. The air is then forced through the main distributing-pipe into the pipe 19 and through the hollow axle and the connecting-tube and 125 spoke into the rear-wheel tire, the pump being kept in motion sufficiently long to inflate the tire to the density desired. Should the rider desire to inflate the front wheel, the valve 43^a is closed and the valve 45^a opened. When thus adjusted, the air will flow through the pipe 20 and the rubber tube 20^a and into 130 one of the front forks and axle and from thence through its radial tube or spoke to the

front tire. As soon as the tires are inflated to the density desired the rider shifts the rod 10 in a reverse direction to admit the clutch automatically moving to a released position and drop, throwing the eccentric out of gear.

5 In Fig. 6 I have illustrated a somewhat modified form of my invention, in which the pump is located within one of the horizontal tube-sections of the bicycle-frame, the eccentric in this case being mounted on the crank-axle adjacent the inner face of the large or treadle drive-gear, said eccentric being connected to the pump with the usual pivotal piston-rod connections. In this form, as also 10 in the other form described, the pump is provided with a blow-off valve to allow the escape of air when the pressure becomes too high. The main distributing-pipe has its rear-wheel portion 19^a and its front-wheel portion 20^b also provided with cut-off valves 19^b and 20^c. In this construction the discharge ends of pipes 19 and 20 have flexible portions 51, which connect with short tube connections 52, in turn connected with the outer end of 15 the hollow axles by the union-nuts 53^a. In this construction the hollow axles are connected with the tires by the radial tubes, the same as in the other construction hereinbefore referred to. While I have not shown it 20 in the drawings, it is obvious in practice the crank-axle shaft is also provided with clutch mechanism similar to that described for the construction shown in Fig. 1, which is operated by the handle and the rod 10 the same 25 as in the other form, the operation of this modified arrangement of my invention being precisely similar to that hereinbefore described.

30 In Fig. 7 I have shown a still further modification of my invention, in which the eccentric is shown as being applied directly on the wheel-axles. In this construction a rocker-post 29 is provided to admit the eccentric-pump having a proper motion while running. In this 35 form a rubber tube 30, extending from the top of the rocker-post to the tire, is provided, which connects with the air-feed tube 40^a.

40 In Fig. 8 I have illustrated a still further modified arrangement of my invention, particularly referring to the means for connecting the discharge end of the air-distributing pipes to the hollow axle. In this construction the distributing-pipe 53, which passes through the crown of the front forks, extends 45 down within one of the side forks and near the lower end, which extends outward and terminates into a threaded neck, which is joined with the hollow axle by an air-tube section 58, which screws up in the neck 59 and down 50 into the threaded orifice 60 of the hollow axle. By providing this form of connection when desired the operator can take the wheel off by screwing the tube 58 up into the portion 55 59 until its lower end disengages the axle.

55 From the foregoing description, taken in

connection with the accompanying drawings, it is thought the operation and advantages of my invention will be readily understood.

While I have described in detail the peculiar construction of parts illustrated in the accompanying drawings to make my invention fully understood, yet it is obvious that such details of construction may be modified and varied without departing from the scope of the appended claims. For example, the air 70 may be carried by means of a tube within the frame-fork connected directly with the axle, as shown in Fig. 9, or, if desired, the frame-tubing may be used as a means for distributing the air to the axles by providing the 75 same with suitable stop-offs or diaphragms at each side of the pump-chamber.

80 In Fig. 10 I have illustrated one form of connection for joining the pump-rod with the crank-axle. Referring to such figure, 91 indicates the crank-axle; 92 the pitman-rod, which drives the piston. This rod has a sliding head 94 working in the movable slide 93, which in practice is suitably mounted on a frame and has a handle 102 extended up with 85 in convenient reach of the rider, whereby said slide can be moved up or down for the purpose presently explained. As the piston-rod in this construction is provided with expandable clutch portions 97, having ball-seats 101, 95 which are adapted to be moved into a tight frictional contact with the ball 96 on the end of the rod 92, the clamping of the piston-rod members of the said pump being effected by reason of the lower end of such piston-rod 90 members 97 being so arranged as to be engaged by the slide 93 and moved to a gripping position when the said slide is pulled upward and adapted to spring apart to a release position when the said slide is pushed down. 100 By providing this form of pump-rod connection it is obvious the rider can throw the pump into or out of operative condition, as may be desired, such construction of parts forming a practical substitute clutch mechanism here- 105 fore described and illustrated in Fig. 2.

110 Instead of operating the pump-shifting mechanism by lever devices held adjacent the driver's seat the same may be operated by devices held on the handle-bars comprising 115 suitable bell-crank-lever mechanisms operated to shift the pitman-rod, joined with the clutch devices by a direct hand manipulation and returned to the normal position by suitable spring mechanism, one form of such devices being illustrated in Fig. 11.

120 To properly center the washers 34 34^a and 35 35^a and the spring 36, I provide pins which project from the inside on the axle of the air-chamber Z from the collars 32^b, as clearly 125 shown in Figs. 3 and 3^a, said pins passing through apertures in the aforesaid washers and within the spring 36. By providing the projecting pins it is obvious the washers and the spring will be held from tight frictional 130

contact with the axle and be practically free therefrom.

To keep the eccentric from touching the crank-axle, it may be mounted on a suitably arranged cuff member, as shown in Fig. 2.

Having thus described my invention, what I claim, and desire to secure by Letters Patent, is—

1. A bicycle-pump mechanism, comprising
  - 10 in combination with the frame, a pump operatively connected with a movable part of the wheel-frame; a wheel-axle bearing having an air-collecting space; the crank-axle having an outlet-port communicating with the said air-space; valved lead-pipes carried on the frame and discharging into the tires, said leads having air-tight joint connections with the crank-axle outlet-port, substantially as shown and described.
  - 20 2. The combination with the wheel, the inflatable tire therefor and the wheel-axle having an air inlet and outlet, said outlet having connections with the inflatable tire; the pump having operating means adapted to be thrown into gear with a movable part of the machine, said pump having air-distributing pipes, rubber tubes, and the detachable pipe-section joining said pipes and rubber tubes, and the air-inlet of the wheel-axle.
  - 30 3. The combination with the bycicle-frame, including the inflatable tires and wheel-axes, having air inlets and outlets, the outlets being connected with the inflatable tires; of a pump carried on the wheel-frame having operating-gearing adapted to be thrown in and out of mesh with the drive mechanism of the machine; air-distributing pipes and rubber tubes connecting the pipe and the air-inlets of the axle, said distributing-pipes including
    - 35 40 flexible end portions and detachable connections for joining said end portions with the air-inlets of the axle.
  - 40 4. The combination with the machine-frame, the wheels, the pneumatic tires thereon and the hollow axles, said axles having air inlets and outlets, and the connections joining the outlets of the axles with the pneumatic tire; of a pump carried on the frame having its piston-rod geared with the crank-axle of the machine; said pump having distributing-pipes
    - 45 50 19 20, the ends of said pipes having flexible portions; the hollow inlet having a female funnel member; the flexible ends of the distributing-pipes having male funnel members
      - 55 and means for holding the two funnel mem-

bers in air-tight connection, substantially as shown and described.

5. In a bicycle-pump mechanism of the character described; the combination with the wheels having inflatable tires, and axles having air inlets and outlets, the outlets having communication with the tire; of a pump having distributing-pipes whose terminals connect with the inlets of the axles; and an eccentric mounted on the crank-axle connected to the pump, said eccentric being loosely mounted on said crank-axle; a sliding clutch mechanism for locking the eccentric to the crank-axle, said mechanism including a reciprocally-movable collar 9, having a notched way, and a reciprocating rod 10, having oppositely-projecting lugs 12 12^a, engaging the notched way of the collar 9, all being arranged substantially as shown and for the purposes described.

6. In a bicycle-pump mechanism of the character described, the combination with the pump; the operating mechanism therefor, and the distributing-pipes; of the wheel-axle comprising a spindle-casing having solid inside portions 32^a 32^b; washers 34 34^a and 35 35^a; an interposed spring 36; detachable disks 32^b 32^a, said spindle having an air-channel discharging into the axle-casing and having its inlet connected with the terminal of the air-distributing pipe, said axle-casing having a discharge communicating with the tire, all being arranged substantially as shown and described.

7. In an improved bicycle mechanism of the character described; the combination with the air-pumping mechanism carried on the axle, including a distributing-pipe adapted to be connected to the axle; of the axle comprising a spindle having a hollow portion communicating at one end with the distributing-pipe and discharging into an air-collecting space within the hub, said space having communication with the tire; the head portion having internally-threaded annular collars; disks 32^b and 32^a, detachably fitted in such collars; the axle having disk members 40 40^a, adapted to engage the disks 32^b 32^a; washers 35 35^a and 34 34^a, fitted on the spindle; and an interposed spring 36, all being arranged substantially as shown and for the purposes described.
